[57] **CLAIM**

The ornamental design for a creche imbedded among branches of an artificial Christmas tree, as shown and described.

DESCRIPTION

FIG. 1 is a front elevational view showing my new design of a creche imbedded among branches of an artificial Christmas tree;

FIG. 2 is a right side elevational view thereof;

FIG. 3 is a left side elevational view thereof;

FIG. 4 is a top view thereof;

FIG. 5 is a frontal perspective view thereof;

FIG. 6 is a right oriented perspective view thereof;

FIG. 7 is a left oriented perspective view thereof;

FIG. 8 is a front elevational view of detail of the creche portion of the design;

FIG. 9 is a right oriented perspective view of detail of the creche portion of the design;

FIG. 10 is a left oriented perspective view of detail of the creche portion of the design;

FIG. 11 is a right posterior perspective view of detail of a portion of the creche in the design; and,

FIG. 12 is a left posterior perspective view of detail of a portion of the creche in the design.

The creche is not visible in the rear and bottom views of the artificial tree and those views are disclaimed as part of the design.

The characteristic feature of the design resides in the placement of the creche among the branches of an artificial Christmas tree instead of under the tree or elsewhere apart from the tree.
